UNITED STATES PATENT OFFICE.

ALFRED W. FRENCH, OF PIQUA, OHIO.

PRESS-PLATE.

1,256,678.

Specification of Letters Patent. Patented Feb. 19, 1918.

Application filed June 10, 1916. Serial No. 102,972.

To all whom it may concern:

Be it known that I, ALFRED W. FRENCH, a citizen of the United States, residing at Piqua, in the county of Miami and State of Ohio, have invented a new and useful Improvement in Press-Plates, of which the following is a specification.

This invention relates to press plates analogous in some respects to those shown in my co-pending application 24,512, filed April 28, 1915, which are used in presses for expressing oil from previously formed cakes of oil bearing material.

Cotton seed presses heretofore have been provided with press plates forming box-like structures which telescope so as to prevent the cake from spreading or being squeezed out from between the plates while being compressed. In these prior constructions the box-like structures require a relatively large amount of vertical space, so that only comparatively few cakes can be compressed at one time in a press. It has been found that a previously formed cake can be subjected to considerable pressure before the tendency to spread or squeeze out becomes serious.

One of the objects of this invention is to provide press plates consisting of main or supporting plates and smaller plates secured thereto, and retaining walls so arranged on the main plates and proportioned as to telescope with the adjacent smaller plates or other equivalent parts of the press plates after the press plates have been partly moved together and before the cake begins to spread. In this way the press plates and retaining walls occupy less space vertically and thus make it possible to press a larger number of cakes at one time in a press. Other objects of the invention are to provide press plates of this kind with retaining walls or dams of improved construction and arrangement which serve to guide the cakes when placing them in the press and facilitate the releasing and removal of the cakes after they have been compressed; also to provide the retaining walls with means for permitting the escape of all of the oil expressed from the cake and preventing the same from returning to the cake when the pressure is relieved; also to so construct the press plates and cake retaining means as to prevent the pinching of the press cloths between the press plates when the cakes are being compressed; also to improve the construction of

devices of this kind in other respects herein-after mentioned and claimed.

In the accompanying drawings:

Figure 1 is a plan view of a press plate embodying the invention with the supporting plate thereof, partly broken away to show the small plate.

Fig. 2 is a side elevation thereof.

Fig. 3 is a fragmentary transverse sectional elevation, on an enlarged scale, of two press plates showing the same in positions which they occupy relatively to each other before pressing the cake.

Fig. 4 is a similar view thereof showing the two plates in the position in which the cake has been partly compressed.

Fig. 5 is a similar view thereof showing the two plates in the positions which they occupy when the cake has been fully compressed.

Fig. 6 is a fragmentary plan view of one of the press plates.

Fig. 7 is a fragmentary transverse sectional elevation of three press plates of a modified construction showing the upper two plates in the positions which they occupy before the cake is compressed, and showing the lower two plates in the positions which they occupy when the cake is fully compressed.

Fig. 8 is a similar view of another construction.

The press plate comprises a main or supporting plate A and a smaller plate B which is secured to the lower face of the supporting plate by any suitable means, such as screws or the like a. The main supporting plate is provided with the usual notched portions a' a'' near the front and rear corners thereof for links or devices (not shown) which connect adjacent plates. Any other suitable means for connecting the press plates may be employed. The two component plates or portions A and B of each press plate are provided with a plurality of oppositely arranged registering grooves extending longitudinally of the plates and forming oil draining channels C between the two portions of each press plate, and the main or supporting plate is provided with numerous small perforations c for conducting the oil from the upper surface of the plate to the oil draining channels. The upper and lower surfaces of the press plates are preferably provided with ridges or corrugations

c' which prevent the stretching or spreading of the press cloths when the meal cakes are subjected to pressure. These parts in themselves constitute no part of this invention 5 and except as hereinafter explained may be of any suitable construction.

Each press plate A is provided on its upper face at opposite sides with two cake-retaining strips or walls which are arranged

10 so that the smaller plate B of the next press plate above can telescope between said walls when the press plates are moved together to compress the cake, the retaining walls preventing the spreading or squeezing out of

15 the cake when the same is being compressed. The cake-retaining strip or wall shown in Figs. 1 to 6 inclusive consists of a metal bar D suitably secured by rivets *d* on the upper face of the supporting plate. Each bar D

20 has an upwardly projecting flange or part *d'* and is provided at its inner side, or side adjacent to the meal cake, with an inclined face *d*². The lower edges of these inclined faces engage with the side edges of the cake

25 or press cloth at the bottom of the cake to properly center and guide the cake as it is being inserted between the press plates.

When the cake has been fully compressed it can be readily removed from engagement

30 with the inclined face of the press plate by inserting a thin bar or blade of any suitable kind under the cake adjacent to the inclined face *d*². This can be done from the front side of the press and avoids the necessity of driving the cakes forwardly from the rear of the press, as is necessary in the case of presses provided with the rearwardly converging retaining walls with upright sides heretofore used. The compressed cake

40 when thus released from engagement with the retaining wall can be readily pulled forwardly out of the press. Thus one man at the front of the press can readily release and remove the cakes.

45 The small plate B is made slightly wider than the meal cake to be compressed and the retaining bars are so spaced that the small plate can enter between the flanges *d'* thereof, as shown in Fig. 5, when the cake is being compressed. By providing the retaining wall with the inclined face *d*², the bottom of which acts as a guide to assist in the positioning of the oil cake between the plates, the pinching of the portions of the

55 press cloth at the upper edges of the cake is prevented since the inclined faces of the retaining bars space the meal cake at some distance from the flange or upper part *d'* of the retaining wall.

60 When the cake has been fully compressed as shown in Fig. 5, it is desirable to drain all of the oil which has been expressed from the cake away from the edges of the cake so that when the pressure is relieved none of the oil

65 will be again absorbed by the cake. For this

purpose slots or incisions E are provided at intervals through the wall *d'* through which any oil which might be held in the space between the wall *d'* and the side of the small plate B will drain out so that it cannot again 70 return to the cake when the pressure thereon is relieved. Any other means for draining the oil from the space between the wall and the small plate may be employed if desired.

In the construction shown in Fig. 7, the 75 smaller plate B' on the lower face of the supporting plate A' has its side edges bent downwardly or is formed with depending lips *f* having concaved under-faces *f'*. The upper face of each supporting plate A' is 80 provided with a retaining bar G of substantially angular shape having an upwardly extending flange or leg *g* forming a cake-retaining wall. In this construction the depending lip *f* reduces the space or gap between the small plate and the retaining wall *g* when the parts are in the position which they occupy before the compressing of the cake has begun. The retaining bar G, in this construction, is not provided with an inclined inner face, but its inner face is upright and the bars are placed with their upright inner faces the same distance apart as the lower edges of the inclined faces *d*² in the first construction. The pinching of the 90 press cloth between the small plate and the wall *g* is prevented by the depending lip *f* and the curved portion *f'* of the plate B' adjacent to the lip. During the preliminary pressing of the cake the upper portion of the 95 press cloth tends to follow the curvature *f'* of the small plate B' so that the outer edges of the upper portion of the press cloth are bent downwardly by the curved portion of the plate, as shown in the case of the cake 100 between the lower two plates in Fig. 7, so that if the upper edge of a press cloth extends beyond the lip *f*, it will be drawn inwardly by the curvature *f'* of the small plate. 105

In this construction the upwardly extending flanges or walls *g* of the retaining bar are also provided with transverse slits or incisions for draining the oil from the space between the small plate and the retaining 115 wall G. The upper edge of the retaining wall *g* is curved or beveled as shown at *g'* in order to guide the small plate into proper telescopic relation between the retaining walls in case two adjacent press plates become slightly displaced with regard to each other. In this construction the upright inner faces of the walls G act as guides for the cake when inserting it into the press. 120

In the modified construction shown in Fig. 125 8, the small plate B² is substantially the same as the small plate used in the construction shown in Figs. 1 to 6, and the retaining bar is similar to the one provided in the construction shown in Fig. 7. The adj- 130

- cent edges *h* and *i* of the small plate and retaining bars respectively are beveled or inclined in such a manner as to guide the small plate into telescopic arrangement in regard 5 to the retaining bars in case adjacent press plates become slightly displaced and also for the purpose of preventing the pinching of the press cloth between the adjacent plates.
- 10 By means of the several constructions shown in the drawings the upper edges of the retaining bars and the lower edges of the small plates are separated from each other when the press plates are fully separated, or before the cakes are compressed, 15 to such a degree that the preliminary compression of the cakes may be accomplished before the small plates enter between the retaining walls of adjacent press plates.
- 20 The telescoping therefore does not take place until it is actually necessary since the spreading of the cake does not take place to any appreciable degree before the oil begins to flow from the cake, and this does 25 not occur until after the cakes have been partially compressed. By means of this arrangement the press plates can be made comparatively thin so that they occupy less space vertically in a press than the plates 30 of prior constructions, and at the same time the spreading of the cakes to such a degree as to prevent the edges thereof from being properly pressed is avoided. The capacity of a press provided with plates of this kind 35 is therefore considerably increased. By securing the retaining bars or walls on the upper faces of the press plates the retaining bars act as guides for assisting in properly positioning the cake between the press plates. 40 By so constructing the small plate and retaining bars as to permit the small plate to enter between the retaining bars, the open space between the upper edges of the retaining walls and the adjacent plate 45 can be made considerably less than in constructions in which the small plate does not enter between the retaining walls, thereby making it possible to construct the retaining means of sufficient height to positively 50 prevent a spreading of the meal cake. The means provided for preventing the pinching of the press cloth between adjacent press plates greatly increases the life of the press cloth and decreases the cost of operation.
- 55 I claim as my invention:
1. Press plates adapted to be arranged one over another in a press and each comprising a supporting plate and a separate narrower plate secured on the underside of 60 said supporting plate, said plates being of approximately equal thickness and having drainage channels formed between them, and said supporting plate having perforations leading to said drainage channels, and 65 cake retaining and guide bars projecting
  2. Press plates adapted to be arranged one over another in a press and each comprising a supporting plate and a separate narrower plate secured on the underside of 70 said supporting plate, said plates having being such that when the press plates are fully separated in the press an open vertical space is left between the retaining bar and narrower plate of adjacent press plates, and the narrower plate of each press plate 75 being arranged and being of a width adapting it to enter between the retaining bars of the next press plate when the press plates are moved toward each other.
  3. Press plates adapted to be arranged one over another in a press and each comprising a supporting plate and a separate 80 narrower plate secured on the underside of said supporting plate, said plates having grooves in their adjacent faces which register to form drainage channels between the 85 supporting and narrower plates, and said supporting plate having perforations leading to said drainage channels, and cake retaining and guide bars projecting upwardly from the upper sides of said supporting 90 plates, the total depth from the lower edge of said narrower plate to the upper edge of the retaining bar of one press plate being such that when the press plates are fully separated in the press an open vertical space 95 is left between the retaining bar and narrower plate of adjacent press plates, and the narrower plate of each press plate being arranged and being of a width adapting it to enter between the retaining bars of the 100 next press plate when the press plates are moved toward each other.
  4. Press plates adapted to be arranged one over another in a press and each comprising a supporting plate, and a separate 105 narrower plate secured on the underside of said supporting plate, said plates having oil drainage channels formed between them, and said supporting plate having perforations leading to said drainage channels, and 110 cake retaining and guide bars projecting upwardly from the upper sides of said supporting plates and being spaced apart a distance sufficient to adapt said narrow plate of one press plate to enter between the upper portions of said bars of the next press plate when the press plates are moved toward each other, the lower portions of said retaining and guide bars inclining downwardly and inwardly to center and guide 115 the cake and facilitate the releasing of the compressed cake, the total depth from the lower edge of the narrower plate to the upper edge of the retaining and guide bar of one press plate being such that when the press plates are fully separated in the press an open vertical space is left between the 120 retaining and guide bar and narrower plate of adjacent press plates.
  5. Press plates adapted to be arranged 125

one over another in a press and each comprising a supporting plate, and a separate narrower plate secured on the underside of said supporting plate, said plates having oil 5 drainage channels formed between them, and said supporting plate having perforations leading to said drainage channels, and cake retaining and guide bars projecting upwardly from the upper sides of said supporting plates and being spaced apart a distance sufficient to adapt said narrow plate of one press plate to enter between the upper portions of said bars of the next press plate when the press plates are moved toward 10 each other, said narrower plates being provided with down-curved edge portions for 15

preventing the press cloths from being pinched between said plates and said retaining and guide bars, the total depth from the lower edge of the narrower plate to the upper edge of the retaining and guide bar of one press plate being such that when the press plates are fully separated in the press an open vertical space is left between the retaining and guide bar and narrower plate 20 of adjacent press plates.

Witness my hand, this 7th day of June, 1916.

ALFRED W. FRENCH.
